UNITED STATES PATENT OFFICE.

JOSEPH T. BAILEY, OF PHILADELPHIA, PENNSYLVANIA.

DESIGN FOR A BADGE OR SIMILAR ARTICLE.

SPECIFICATION forming part of Design No. 32,304, dated March 6, 1900.

Application filed February 2, 1900. Serial No. 3,754. Term of patent 14 years.

To all whom it may concern:

Be it known that I, JOSEPH T. BAILEY, a citizen of the United States, residing in the city and county of Philadelphia, State of Pennsylvania, have invented and produced a new and original Design for a Badge or Similar Article, of which the following is a specification, reference being had to the accompanying drawings, forming part thereof.

10 The leading feature of my design for a badge or similar article is, first, a body composed of the representation of a cross-shaped figure, a wreath, an anchor, and stars; next, a seal composed of the representation of a group of beings, as will be hereinafter set forth, and, finally, a decorated suspension-bar.

15 Figure 1 represents a view of the obverse of a badge or similar article embodying my design. Fig. 2 represents a view of the reverse thereof.

In the drawings, A designates a badge or similar article, the body of the same consisting of the representation of a wreath B and

the representation of a cross-shaped figure C, 25 whose limbs join said wreath, the representation of an anchor D on said cross-shaped figure, and the representation of stars E on the wreath at the inner corners of the cross.

F designates the seal, the same consisting 30 of the representation of a soldier and a sailor in the act of protecting a widow and orphan, as at G, and an annular border H.

J designates the ribbon, and K the bar from which the badge is suspended, said bar 35 having representations of corps or service marks thereon and being surmounted by an eagle L and a sunburst M.

Having thus described my invention, what I claim as new, and desire to secure by Letters 40 Patent, is—

The design for a badge or similar article, substantially as shown and described.

JOS. T. BAILEY.
